UNITED STATES PATENT OFFICE.

PAUL BUTLER, OF LOWELL, MASSACHUSETTS.

BRAIDING-MACHINE.

1,091,805.

Specification of Letters Patent. Patented Mar. 31, 1914.

Application filed November 26, 1897. Serial No. 659,888.

To all whom it may concern:

Be it known that I, PAUL BUTLER, of Lowell, county of Middlesex, State of Massachusetts, have invented an Improvement 5 in Braiding-Machines, of which the following description, in connection with the accompanying drawings, is a specification, like letters on the drawings representing like parts.

This invention has for its object to simplify the construction of that class of braiding machines employed in the manufacture of cords, ropes, etc.

In accordance with my invention the carriers of flier shape containing the cops or spindles of twine are moved in a path between a top and bottom plate, certain carrier-plates adjacent the said top and bottom plates constituting bearings for the journals 20 of the carriers, each carrier having two journals one above and the other below the cop or spool containing the twine to be made into a coil or rope.

By supporting each carrier near its upper 25 as well as near its lower end the movements of the carriers are steadier and more uniform than if supported at the lower end only, and any desired tension may be put upon the twine without interfering with the proper working thereof; and also thereby the life of the carriers is much increased, larger and longer bobbins may be used, and the machine is given increased capacity.

The carrier plates are provided with similar switches or automatic dogs, to move the carriers alternately into and out of the carrier plates and thereby the strain on the carriers is even at top and bottom; the switches themselves also constitute a novel feature of 40 my invention.

The details of construction of my improved braiding machine will be more fully understood from the following description, and the particular features of novelty there- 45 of will be pointed out in the appended claims, reference being had to the description and accompanying drawings.

In the drawings, illustrative of a preferred embodiment of my invention, Figure 50 1 is a side elevation of the complete machine. Fig. 2 is a top plan view thereof, a portion of the winding mechanism being omitted. Fig. 2^a is a detail of the stop motion plate; Figs. 3 and 4 are fragmentary views in horizontal section, showing similar portions of the top plate and upper carrier

plates illustrating successive positions respectively of the switches and carriers with their contained bobbins. Figs. 5 and 6 are fragmentary horizontal sectional views 60 showing modified forms of switches. Fig. 7 is a horizontal section taken substantially on the line 7—7, Fig. 1. Fig. 8, is a vertical section taken on the line 8—8, Fig. 4. Fig. 9 is a central vertical section of a bobbin and 65 bobbin carrier, also showing the tension device in elevation. Fig. 10, is an enlarged central vertical section of the tension device. Fig. 11 is a top plan view thereof. Fig. 11^a a detail of the stop pin; Fig. 12 is a central vertical section taken on the line 12—12, 70 Fig. 2, showing the take-up and tension regulator in side elevation. Fig. 13 is a vertical section on the line 13—13, Fig. 2, looking toward the left.

The frame A, herein shown as a skeleton frame comprising four vertical bars *a* and a base *a'*, is supported on a suitable standard A', having its legs *a'* secured to the floor, and carries at its upper end and at its lower 80 end, similar top and bottom rings B, B', said rings having like series of notches *b* and flanges *b'*, the former of which are adapted to receive at the proper times the journals of the carriers and retain them while the journals of other carriers are engaged by carrier plates to be described.

Within the stationary rings B, B', of the frame A, is a central vertical shaft C having secured thereto similar top and bottom 90 plates D, D', respectively, in the planes of said top and bottom rings, said plates being guided by and having bearings against the inner edges of the flanges of said respective rings. The top and bottom plates D, D', 95 are provided with a plurality of recesses herein shown as four in number, in which are mounted carrier plates E, each fixed on a shaft *e'*, as clearly shown in Fig. 8, and provided with peripheral flanges *e*², Fig. 8, 100 adapted to rest on corresponding flanges *d*, provided as bearings therefor on the top and bottom plates respectively.

The carrier plates are herein shown as having three equi-distant recesses *e*³⁰, see 105 Figs. 3 and 4, adapted to receive the journals *f*, *f'*, of the bobbin carriers F, see Fig. 8.

The shaft *e'* has a journal bearing at *g*, *g'*, in a spider G, Figs. 7 and 8, fast on the central shaft C, and between these bearings 110 a toothed pinion *e*³ is fixed on the shaft by suitable means, as by a pin *e*⁴, said pinion

meshing with internal gear teeth a^3 on the base a' , said base also having an annular ledge a^4 to steady the spider G. The spider G is provided with a bevel gear g^2 , secured to the underside thereof in mesh with a driving pinion h , on the inner end of the driving shaft h' , having bearings a^5 , a^6 , respectively in the frame of the machine and a bracket a^7 secured thereto, between which bearings are a usual fast pulley a^8 , and loose pulley a^9 having a belt shifter a^{10} pivoted at a^{11} on an upright a of the frame. The gear g^2 also serves to drive the winding and take-up mechanism by means of a pinion k in mesh with the gear g^2 , and a pinion k' in mesh with a bevel gear k^2 at the inner end of a vertical shaft k^3 provided with a worm k^4 at its upper end, geared to opposite worm wheels k^5 , k^6 , on parallel horizontal shafts k^7 , k^8 , having suitable bearings at the top of the machine, Fig. 2, in a bracket A^2 , Fig. 1.

From the above description it will be evident that rotation of the drive shaft h' serves to rotate the central vertical shaft C and thereby correspondingly rotate the top and bottom plates D, D', and spider G. The toothed pinions e^3 are rotated by engagement of said pinions with the teeth a^3 , as the bobbin carriers are revolved by the rotation of the spider G, and the top and bottom plates D, D'.

In order that the carrier plates may pick up the proper bobbins at the proper intervals, my machine being herein shown as arranged to pick up the bobbins alternately, I have provided the top and bottom plates D, D', with switches m , similarly arranged on the respective plates, said switches being shown in Figs. 2-4 as pivoted at m' , the pivots having bearings in the plates themselves and in journal arms m^2 removably secured for convenience by bolts m^3 in channels d' formed between opposite ribs d^2 , d^3 , on the plate. The switches m , as shown in Figs. 2-4, are in the form of dogs, having three arms m^4 , m^5 , m^6 , the latter engaging stops m^7 . The operation of these switches will be readily understood from Figs. 3 and 4, showing successive positions assumed thereby in the forward rotation of the plates, the relative direction of rotation of the top and bottom plates and the carrier plates being indicated by the arrows.

Viewing Fig. 3, it will be observed that the switch m is held raised by the engagement of the bobbin carrier 1 with its arm m^6 , so that the bobbin carrier 2, which is in one of the notches b of the ring B cannot be engaged by the arm m^4 of said switch as the plate D moves the latter toward said bobbin carrier 2; accordingly the switch is carried over said carrier 2, and the latter striking against the arm m^6 thereof turns the switch into the position shown in Fig. 4, in which position the switch is brought to rest by the

engagement of the arm m^4 with the ring B, the bobbin carrier 1 in the meantime having been carried around by the carrier plate as there shown. The switch in question is now in position to catch bobbin 3, and prevent its remaining in the ring B, causing it to be carried around by the rotation of the carrier plate E. Similar switches m^7 are reversely placed opposite the switches m in order to perform the same offices last described, in case it is desired to run the machine in the opposite direction to that indicated by the arrows.

Instead of the three armed switches shown in Figs. 2-4, two armed switches may be used as shown in Fig. 5, where m^8 designates a switch having a spring s normally holding it in engagement with the ring B in which case a bobbin carrier in the position of the carriers in Fig. 3 would serve to press back the switch m^8 against said spring and hold it away from the ring B, and in Fig. 6 where m^9 designates a switch normally held by a spring s' away from the ring B in which case the passage of a bobbin carrier beneath it into the position shown in Fig. 6, would press it against said ring ready to pick up the next bobbin carrier and deliver it to the carrier plate E.

Referring to the mechanism at the upper part of the machine shown best in Figs. 1, 2, and 12, it will be observed that the shafts k^7 , k^8 , are provided at their forward ends with similar take-up rolls K, K'.

The strands of twine are taken from the respective bobbins without rotating the latter and are led over a direction plate or spreader N on the upper end of the shaft C, where they are braided together to form a cord or rope, as shown in Fig. 12, the braid receiving a central filling strand through the perforated center n of the plate N and shaft C, the cord or rope being thence led over a guide pulley K^2 to the take-up rolls K, K', from which the cord or rope passes over a pulley block K^3 , and down under the lower wheel K^4 of a tension regulator, said regulator having also an upper wheel K^5 journaled at the free end of a lever k^9 , pivoted for convenience on a shaft k^7 and held downwardly by a spring s^2 , adjustably connected to said lever by a link k^{10} . The wheels K^4 , K^5 are provided with teeth similar to gear wheels so that they mesh one with another, and they also both have V-shaped grooves in their peripheries, these grooves being cut into the teeth, as shown best in Fig. 2, for the purpose of receiving the rope. The result is that as the rope passes between the wheels K^4 , K^5 and in frictional engagement therewith the positively driven wheel K^4 brings a constant pull on the rope, this pull being determined by the tension to which the wheel K^5 is held by its spring s^2 . This tension regulator serves to make the feed

even in the take-up, and yet leave the latter free to act as a usual friction take-up.

From the tension regulator the cord passes over and around a direction wheel K^6 and 5 thence over pulley K^7 , and thence down to the winding drum or reel P .

The reel P is driven by an endless cable p which passes over a sheave p' at one end of the reel and thence over a double groove pulley p^2 on the shaft k^8 . p^8 is a finger slidably mounted on the rod p^9 and by which the cord is guided as it is wound on the drum. The novel features of this reel have been made the subject of another Patent No. 15 998,231, dated July 18, 1911, the application for which was divided out from this case, and as no claim is herein made to the reel, I do not deem it necessary to further describe the latter.

20 The twine is taken centrally from the bobbins without rotating the latter. Each bobbin is sustained by a bobbin-carrier which consists of top and bottom ends f^4 , f^5 connected by opposite arms f^6 . The ends carry 25 upper and lower journals f , f' , and the former journal f is provided with a central twine passage f^3 through which the twine is led to the tension device comprising a friction plate t , a pivotally-mounted tension 30 member t' which is acted on by a spring t^9 . The twine is taken from the passage f^3 and is carried between the friction plate t and the tension member t' and thence around the 35 stop pin u having a groove u' therein to receive the cord, and thence around a post t^2 projecting from the bobbin carrier, and thence through the pig-tail t^4 .

The above-described bobbin carrier is not herein claimed as it has been made the subject of another Patent No. 1,045,254, dated 40 November 26, 1912.

The groove u' in the stop motion pin u is sufficient to cause the latter to be held in raised position so long as the twine is under 45 tension, but if the twine should accidentally break in passing from the bobbin thereto, the pin u will be permitted to drop until the collar u^{10} meets the plate t , which leaves the lower end of said pin in position to contact 50 with a suitable projection 50 from a plate u^2 , which may be either the whole or part of a circle, said plate, herein shown fully in Fig. 2^a, and only partially in Fig. 2, being of segmental form, and it is of a length sufficient 55 to present three like projections 50, that number of projections being necessary to adapt it to coöperate with a machine having twelve carriers, but these projections will vary as the number of carriers are increased, there being one such projection for 60 each notch of a carrier plate.

The plate u^2 is herein shown as secured to the top ring B by bolts u^3 passing through elongated slots u^4 , said plate being normally 65 held in the position, Fig. 2, by a spring s^4

engaging a pin u^5 on the ring and a pin u^6 on the plate. This plate is provided at its forward end with a lug u^7 normally engaging a catch u^8 secured to the shipper lever a^{10} ; so that when this catch is released by 70 the forward movement of the plate due to contact therewith of a drop pin u , the shipper lever is released and at once moves by its spring s^5 to shift the driving belt from the fast pulley a^8 to the loose pulley a^9 .

In the operation of the machine it will be assumed that the top and bottom plates and the carrier plates therein rotate in the direction of the arrows Figs. 3 and 4, and it will be seen that each of the carrier plates 80 contains in its notches, the journals of two carriers, and that the ring B , contains a carrier in one of its notches between the different carrier plates, and that, viewing Fig. 2, the arms m^4 of the switches m are in their outermost positions adjacent the ring B , it being understood that all the corresponding parts occupy precisely the same positions at the lower ends of the bobbin carriers. As 85 the spider G is rotated by the engagement of the pinion h with the gear g^2 on the spider, the shafts c' of the bobbin carriers will be rotated by the engagement of their pinions e^3 with the stationary gear or rack a^3 as the top and bottom plates rotate with 90 their shaft C , so that the said carrier plates by the aid of the said switches will engage the journals of the carriers immediately ahead of them, and will carry the said carriers with a planetary motion about the 95 shafts c' , at the same time putting back again in the next forward notch of the rings B , B' , the other carrier contained in the notches of the carrier plate, and this latter carrier will be skipped by the switch as 100 the latter progresses, said switch m being then held in its innermost position as shown in Fig. 3, ready to be shifted again to its original position, as soon as the parts progress to the position shown in Fig. 4; this 105 cycle of movements being continued uniformly as the shaft C rotates, the result being that each switch picks up every alternate bobbin, each succeeding switch picking up those bobbins which the preceding 110 switch left.

I have herein shown the rings B , B' , as provided with a series of 12 notches b , and each carrier plate as having three notches adapted to handle twelve carriers, but it is 115 obvious that any desired number of carriers may be placed in a machine of the class described. The carrier plates and rings have a correspondingly greater or less number of notches, according to the number of carriers to be used; and so also, the distance apart of the bottom and top plates may be more or less according to the length of the cop or bobbin which it is desired to use in a carrier.

No undue strain is brought upon the carrier by reason of any increase in length thereof, for the reason that the carrier is positively moved both at its top and bottom ends, its life being thereby prolonged and its operation facilitated. The tension regulator is adjusted by means of the link k^{10} , according to the size and kind of rope being braided. In case a thread should break it will thereby permit the pin u to drop into engagement with the stop motion plate u^2 , releasing the catch u^8 and shipper a^{10} to stop the machine.

I have already suggested three forms of switches and I wish it understood that these and many other variations in form and changes in construction and relation of parts may be resorted to without departing from the spirit and scope of my invention, and I therefore do not limit the latter in any respect otherwise than as expressed in the claims.

Having fully described my invention, what I claim and desire to secure by Letters Patent, is:—

1. In a braiding machine, the combination with top and bottom connected plates, of a central shaft on which said plates are mounted, means to rotate said shaft, a plurality of bobbin carriers, means associated with each of said top and bottom plates to carry said bobbin carriers about in the machine, and upper and lower sets of horizontally swinging bobbin-carrier-operated switches sustained by said upper and lower plates, respectively, and arranged to act positively and simultaneously on the opposite ends of said carriers thereby to direct the latter into the required position.
2. In a braiding machine, the combination with fixed top and bottom rings having notches, of an annular gear, a central vertical shaft, concentric top and bottom plates fixed to said shaft and situated within said rings, means to rotate said shaft and thereby the plates in unison, notched carrier plates between said plates and rings, said carrier plates having pinions in engagement with said annular gear, means to support

said carrier plates, a plurality of bobbin carriers, each extending from the top plate to the bottom plate and adapted to be held in said notches, and bobbin-carrier-operated switches sustained by said top and bottom plates and arranged to swing horizontally into the path of said bobbin carriers and co-operating with said top and bottom plates to cause said bobbin carriers to slide along the switches from the notches of said rings to the notches of the carrier plates in desired order.

3. In a machine of the class described, a bobbin carrier, a shipping lever, holding means normally retaining said shipping lever in inoperative position, a friction plate carried by said bobbin carrier, a tension device movable toward said plate, and a stop motion pin arranged to slide vertically in said friction plate, the twine being led between said tension device and friction plate and wrapped around said pin for normally holding the pin in raised position, slackening of the twine permitting the pin to drop into engagement with said holding means for operating said shipping lever to stop the machine, substantially as described.

4. In a braiding machine, the combination with a central vertical shaft, of top and bottom plates sustained thereby, means to rotate the shaft, a plurality of carrier plates rotatably sustained by each of the top and bottom plates, a plurality of bobbin-carriers engaged and moved about by said top and bottom carrier plates, and an upper set of horizontally swinging switches sustained by the top plate, and a lower set of horizontally swinging switches sustained by the bottom plate, all of said switches being constructed to be actuated by the bobbin carriers and operating to direct the bobbin carriers into required position.

In testimony whereof, I have signed my name to this specification, in the presence of two subscribing witnesses.

PAUL BUTLER.
